(57) **CLAIM**

The ornamental design for a ground paper for food packing, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a ground paper for food packing of the present invention.

FIG. 2 is a front view of the ground paper for food packing of FIG. 1.

FIG. 3 is a rear view of the ground paper for food packing of FIG. 1.

FIG. 4 is a left side view of the ground paper for food packing of FIG. 1.

FIG. 5 is a right side view of the ground paper for food packing of FIG. 1.

FIG. 6 is a plane view of the ground paper for food packing of FIG. 1; and,

FIG. 7 is a bottom view of the ground paper for food packing of FIG. 1.
